(57) **CLAIM**

The ornamental design for a keychain having a solar powered display, as shown and described.

DESCRIPTION

FIG. 1 is a top perspective view of the solar powered display separated from the keychain;

FIG. 2 is a top view of keychain with the solar powered display attachment;

FIG. 3 is a back view of keychain;

FIG. 4 is a side view of keychain with the solar powered display attachment; and

FIG. 5 is a first end view of keychain with the solar powered display attachment; and,

FIG. 6 is a second end view of keychain with the solar powered display attachment.
